H. F. PARKER.

VARIABLE CAMBER RIB FOR AEROPLANE WINGS.

APPLICATION FILED JULY 17, 1919.

1,341,758.

Patented June 1, 1920.

UNITED STATES PATENT OFFICE.

HUMPHREY FRANCIS PARKER, OF DUNEDIN, NEW ZEALAND.

VARIABLE-CAMBER RIB FOR AEROPLANE-WINGS.

1,341,758.

Specification of Letters Patent.

Patented June 1, 1920.

Application filed July 17, 1919. Serial No. 311,432.

To all whom it may concern:

Be it known that I, HUMPHREY F. PARKER, a subject of the King of England, residing at Dunedin, in the Provincial District of Otago and Dominion of New Zealand, have invented certain new and useful Improvements in Variable-Camber Ribs for Aeroplane-Wings; and I do hereby declare the following to be a full, clear, and 10 exact description of the invention, such as will enable others skilled in the art to which it appertains to make and use the same, reference being had to the accompanying drawings, and to characters of reference marked 15 thereon, which form a part of this specification.

The present invention relates, generally, to improvements in aeroplanes; and the invention has reference, more particularly, to 20 a means whereby the speed range of aeroplanes is increased, so that in aeroplanes designed to have the same maximum speed, lower speeds are obtained for taking off and alighting than is possible with machines 25 heretofore constructed, and in aeroplanes designed to have the same minimum speed higher maximum speeds are obtainable than heretofore.

The invention has for its principal object 30 to provide a novel construction of supporting rib, adapted to carry the lifting surface of an aeroplane, or any desired portion of said lifting surface, which automatically operates to vary the camber of said lifting 35 surface or desired portion thereof, to the end that the same is capable of changing its shape and its angle of incidence during flight.

Other objects of the present invention, 40 not at this time more particularly enumerated will be clearly understood from the following detailed description of the same.

With the various objects of my present invention in view, the same consists, primarily, in the novel construction of flexible 45 supporting rib structure for aeroplane wings hereinafter set forth; and the invention consists, furthermore, in the various arrangements and combinations of the several devices and parts, as well as in the details of the construction of said devices and parts, all of which will be more fully described in the following specification, and then finally embodied in the claims which 50 are appended thereto.

The invention is clearly illustrated in the accompanying drawings, in which:—

Figure 1 is a side elevation of my novel construction of supporting rib illustrating its contour when it assumes a streamline 60 shape for high speeds.

Fig. 2 is a side elevation of my novel construction of supporting rib illustrating its contour when it assumes its maximum lifting shape for landing and taking off. 65

Fig. 3 is a partial detail longitudinal section of my supporting rib, drawn on an enlarged scale.

Fig. 4 is a transverse section taken on line 4—4 in said Fig. 3, the same being drawn 70 on a further enlarged scale.

Similar characters of reference are employed in all of the hereinabove described views, to indicate corresponding parts.

Referring now to said drawings, the reference character 1 indicates the front spar of an aeroplane wing, and the reference-character 2 indicates the rear spar of the same, with which spars the rib structures are arranged so as to be properly carried 75 thereby.

The rib structure comprises, essentially, a flexible body-portion A extending between the front spar 1 and rear spar 2, and a rigid tail-portion B extending rearwardly from 85 said rear-spar, but being slidably arranged for movement over the same. Said rigid tail-portion B is connected with said flexible body-portion A in a peculiar and characteristic manner, to be subsequently 90 described.

The flexible body-portion A comprises a flexible upper longitudinal member or strip 3, and a flexible lower longitudinal member or strip 4. Said respective longitudinal 95 members or strips 3 and 4 are anchored or secured by their forward ends to said front spar 1. Said respective longitudinal members or strips 3 and 4 are preferably made of steel having a shallow channel shape in 100 cross-section, with their channel faces turned inward, and the same are designed to flex when a change of shape of the rib structure is effected.

Pivots interconnected between said longitudinal members or strips 3 and 4 are a series of longitudinally spaced compression links 5. Said compression links may be made of any suitable shape and of any suitable material, but, preferably, are of a rigid 110

channel steel construction provided with pairs of perforate ears or lugs 6 at their respective ends. Said longitudinal members or strips 3 and 4 are provided in their side flanges, at the respective locations of pivotal connection of said compression links 5 therewith, with perforate ears 7 between which are received and registered the ears or lugs 6 of said compression links, so that transverse pivoting pins 8 supported by said ears 7 may pass through the ears or lugs 6 to establish the desired pivotal connection between the longitudinal members or strips 3 and 4 and said compression links 5. The function of the compression links is to maintain the longitudinal members or strips 3 and 4 in proper relative spaced relation one to the other at all times and to complete the frame.

Interconnected between the upper and lower longitudinal members or strips 3 and 4, preferably by securing their ends upon the pivoting pins 8 between the ears or lugs 6 of the compression links 5, are a series of diagonal flexible steel bracing straps 9 adapted to arrest deformation of the flexible body-portion A of the rib beyond the desired change of shape effecting its lifting form, and a second series of diagonal flexible steel bracing straps 10 adapted to arrest deformation of the flexible body-portion A of the rib beyond the normal return from its lifting form to its high speed or streamline shape. When the aeroplane wing or lifting surfaces, as supported by novel construction of ribs, is subjected to an overload, such *e. g.* as is likely to occur in flattening out after a steep dive, the compression links 5 together with the diagonal bracing straps 9 provide a truss-like structure, in which a limited amount of rotary motion is permitted between the compression links 5 and the longitudinal members or strips 3 and 4 sufficient to permit the rib to effect desired change of shape; in which truss-like structure the diagonal bracing straps 9 (which when the rib is in its streamline shape are slackened off or bowed) are tautened when the desired change to lifting shape is accomplished so as to limit any further flexing of the longitudinal members or strips 3 and 4. The diagonal bracing straps 10 (which when the rib is in its lifting shape are slackened off or bowed) are tautened when the change to streamline shape is accomplished so as to limit any further flexing of the longitudinal members or strips 3 and 4 beyond that shape, especially when the wing or lifting surface is submitted to abnormal stresses of air-pressure acting upon the upper surfaces thereof, or when the aeroplane is flying in an upside down attitude.

The tail-portion B of the rib structure comprises an upper rigid longitudinal mem-

ber or strip 11 and a lower rigid longitudinal member or strip 12, the same converging relatively toward their rear extremities or trailing ends, and being secured together in rigid relation one to the other by means of intermediate truss-bars 13 secured to said respective members or strips 11 and 12 either as an integral part thereof, or in any other suitable manner. Preferably said tail-portion is made of a suitable metal, and either in a cast or stamped form of construction. The forward extremity of the upper member or strip 11 is securely anchored to the rearward extremity of the upper flexible member or strip 3, by means of rivets 14, or in any other suitable manner. The forward extremity of the lower member or strip 12 is associated with the rearward extremity of the lower flexible member or strip 4 for slidable longitudinal movement relative to the latter; to this end the said forward extremity of the lower member or strip 12 is received in and rides in the channel of said lower flexible member or strip 4, the flanges of the latter having perforate ears 15 at their extremities through which extends a transverse pin 16 adapted to extend laterally across and above said member or strip 12, and serving to prevent displacement of the latter from the channel of said lower flexible member or strip 4. The said rigid tail-portion B is provided adjacent to its forward end with a space 17 through which the rear spar 2 extends. The horizontal dimensions of said space 17 is greater than the width of the spar 2 by the distance of forward travel of tail-portion B as determined by the amount of upward deflection permitted to the flexible body-portion A between the spars 1 and 2, when said flexible body-portion changes from streamline to lifting shape.

The flexible members or strips 3 and 4 may be designed to have sufficient rigidity to enable them to return to and maintain their streamline shape under high speed flying conditions, and yet of sufficient flexibility to enable them to flex to their lifting shape under normal flying load; preferably, however, the flexible members or strips 3 and 4 are made slightly less rigid, or in other words slightly more flexible, than would be necessary if acting alone, and then supplementing the action thereof by aid of a helical compression spring 18 placed between the rear spar 2 and the adjacent vertical truss-member of the tail-portion B immediately in the rear of said spar 2.

Connected with the forward side of the front spar 1 is a light nose-piece 19, preferably made of wood and of convex contour on its outward or forward surface, the same running coincident with the entire outward spread of the aeroplane wing to give a fair shape to the leading edge of the latter.

It will be understood that in the construction of the wings or lifting surfaces of aeroplanes, embodying the novel rib structure above described, that said ribs are mounted 5 in connection with the front and rear spars in desired spaced relation one to the other throughout the extent or spread of the wing or lifting surface, or throughout so much of said extent or spread as it is desired to render 10 automatically variable as to its camber. The fabric of the wing is spread over the supporting structure provided by the spars and interconnecting ribs.

The operation of the ribs to vary the camber of the wing or lifting surface, or of any 15 desired portion of the latter, is automatically accomplished by the functioning of my novel rib structure. The desired changes of shape of the wing or lifting surface being 20 brought about by the changes of pressure upon and distribution of pressure over the wing surface. When the pilot of the aeroplane pulls the control stick back, the attitude of the aeroplane is altered, and the variable 25 portions of the wings thereof instead of lying along the direction of the air flow, are inclined to said flow. The air pressure thus brought into play acts against the variable portions of the wing and causes 30 them to change to the desired shape. The air pressure on the portion of the plane between the front spar 1 and rear spar 2 being greater than the pressure on the portion between the rear spar 2 and the trailing edge, 35 the portion between the spars, to wit, that supported by the flexible body-portions of the ribs is compelled to move or bow upwardly, and the portion between the rear spar and the trailing edge, to wit, that sup- 40 ported by the rigid tail-portions of the ribs is compelled to move or swing downward, thus altering the shape of the plane or variable portion thereof to a maximum lifting shape. When such change of shape occurs 45 the upper and lower flexible members 3 and 4 of each rib flex or bow upwardly, at the same time drawing forward upon the rear spar 2 the rigid tail-portions of each rib, whereby the latter are inclined or swing 50 downwardly from the rear spar, and at the same time the supplementary auxiliary compression springs 18 are placed under compression. When the pilot wishes to fly the aeroplane at maximum speed again, and 55 alters the elevator accordingly to bring the attitude of the aeroplane back to normal, the planes or variable portions thereof are again brought to lie along the direction of air flow, so that the spring action of the flexible members 3 and 4, supplemented by the 60 stored compression of the springs 18, quickly causes the variable ribs to return to or re-assume a streamline shape, and consequently thereby position the lifting surfaces of the 65 planes at a lesser angle of incidence.

My novel invention may be used in that type of aeroplane having two or more planes, one of which is of ordinary construction and the remainder of variable construction employing my novel rib structure; 70 or the invention may be used in an aeroplane having one or more planes in which a portion of each plane is of fixed or ordinary construction while the remainder is of variable construction employing my novel rib 75 structure. In aeroplanes constructed in either manner it is the function of the variable portion of the plane areas to change its shape from a streamline contour to a maximum lifting shape (to wit, giving the 80 upper surface of the wing greater convexity and the lower surface a marked concavity) presented at a greater angle of incidence so as to render the same capable of assisting in supporting the weight of the machine at low 85 speeds, and in landing and taking off. When the aeroplane is flying at high speed the variable portion of the plane areas assume a streamline shape (to wit, giving both the upper and lower surfaces of the wing a 90 comparatively equal and small degree of convexity) presented at a lesser angle of incidence, so as to lie along the direction of air flow, thus offering less resistance or drag, although not contributing materially to the 95 lift of the machine. In such aeroplanes the fixed plane surface carries the whole weight of the machine at high speeds, and a portion only of the weight when landing, while the variable plane surface assists in carrying 100 the weight of the machine when landing or flying at lower speed, but to carry none of the weight when flying at high speed.

While in the claims I have used the term "aeroplane wings" I do not thereby intend 105 to confine myself to the use of my novel ribs in the lifting surfaces of heavier than air machines, but intend that the same may be applied in use to any lifting surface of wing type whether employed in heavier than air 110 machines or in lighter than air machines.

I claim:—

1. A variable camber rib for aeroplane wings having front and rear spars, comprising a flexible body portion having its forward end fixed to said front spar, a rigid tail-portion having a slidable and oscillatable relation to said rear spar, said rigid tail-portion being connected with said flexible body portion whereby flexing of the latter produces an oscillation of the rigid tail-portion. 115

2. A variable camber rib for aeroplane wings having front and rear spars, comprising a flexible body portion having its forward end fixed to said front spar, a rigid tail-portion having a slidable and oscillatable relation to said rear spar, said rigid tail-portion being connected with said flexible body portion whereby upward flexing of 120 125 130

the latter produces a limited forward sliding movement upon and a downward swing from said rear spar of said tail-portion.

3. A variable camber rib for aeroplane wings having front and rear spars, comprising a flexible body-portion between said front and rear spars, a rigid tail-portion mounted on and extending rearwardly from said rear spar, the upper portions of said flexible body-portion and said rigid tail-portion being rigidly united while the lower portions of the same are united for limited longitudinal sliding movement of said tail-portion relative to said body-portion.
4. A variable camber rib for aeroplane wings having front and rear spars, comprising a flexible body-portion consisting of upper and lower flexible longitudinal members having their forward ends fixed to said front spar, a series of compression links intermediate said members and pivotally connected with the latter, means for limiting the flexing movements of said members, and a rigid tail-portion having a slidable and oscillatable relation to said rear spar, said rigid tail-portion having the upper portion of its forward end fixed to the rear end of said upper flexible member and the lower portion of its forward end slidably related to the rear end of said lower flexible member.

5. A variable camber rib for aeroplane wings having front and rear spars, comprising a flexible body portion consisting of upper and lower flexible longitudinal members having their forward ends fixed to said front spar, a series of compression links spaced longitudinally intermediate said members, means for pivoting the ends of said compression links respectively to said upper and lower flexible members, flexible diagonal bracing straps interconnected between said upper and lower flexible members to limit the flexing movements thereof, and a rigid tail-portion having a slidable and oscillatable relation to said rear spar, said tail-portion having the upper portion of its forward end fixed to the rear end of said upper flexible member and the lower portion of its forward end slidably related to the rear end of said lower flexible member.

6. A variable camber rib for aeroplane wings having front and rear spars, comprising a flexible body portion consisting of upper and lower flexible longitudinal members having their forward ends fixed to said front spar, a series of compression links spaced longitudinally intermediate said members, means for pivoting the ends of said compression links respectively to said upper and lower flexible members, a series of flexible diagonal bracing straps interconnected between said upper and lower flexible members to limit the flexing thereof when

desired change of shape from streamline to lifting form is attained, a second series of flexible diagonal straps interconnected between said upper and lower flexible members to limit the flexing thereof when desired change of shape from lifting to streamline form is attained, and a rigid tail-portion having a slidable and oscillatable relation to said rear spar associated with said upper and lower flexible members and operated by the flexing movements thereof.

7. A variable camber rib for aeroplane wings having front and rear spars, comprising a flexible body portion consisting of upper and lower flexible longitudinal members having their forward ends fixed to said front spar, a series of compression links spaced longitudinally intermediate said members, means for pivoting the ends of said compression links respectively to said upper and lower flexible members, a series of flexible diagonal bracing straps interconnected between said upper and lower flexible members to limit the flexing thereof when desired change of shape from streamline to lifting form is attained, a second series of flexible diagonal straps interconnected between said upper and lower flexible members to limit the flexing thereof when desired change of shape from lifting to streamline form is attained, and a rigid tail-portion having a slidable and oscillatable relation to said rear spar, said tail-portion having the upper portion of its forward end fixed to the rear end of said upper flexible member and the lower portion of its forward end slidably related to the rear end of said lower flexible member.

8. A variable camber rib for aeroplane wings having front and rear spars, comprising a flexible body-portion consisting of upper and lower flexible longitudinal members having their forward ends fixed to said front spar, a series of compression links spaced longitudinally intermediate said members, means for pivoting the ends of said compression links respectively to said upper and lower flexible members, a series of flexible diagonal bracing straps interconnected between said upper and lower flexible members to limit the flexing thereof when desired change of shape from streamline to lifting form is attained, a second series of flexible diagonal straps interconnected between said upper and lower flexible members to limit the flexing thereof when desired change of shape from lifting to streamline form is attained, a rigid tail-portion having a slidable and oscillatable relation to said rear spar, said tail-portion having the upper portion of its forward end fixed to the rear end of said upper flexible member and the lower portion of its forward end slidably related to the rear end of said lower flexible member and spring

means arranged between said rear spar and said tail-portion to supplement the tension of said upper and lower flexible members.

9. A variable camber rib for aeroplane wings having front and rear spars, comprising a flexible body portion consisting of upper and lower flexible longitudinal members having their forward ends fixed to said front spar, a series of compression links spaced longitudinally intermediate said members, means for pivoting the ends of said compression links respectively to said upper and lower flexible members, flexible diagonal bracing straps interconnected between said upper and lower flexible members to limit the flexing movements thereof, and a rigid tail-portion having a slidable and oscillatable relation to said rear spar, said tail-portion having the upper portion of its forward end fixed to the rear end of said upper flexible member and the lower portion of its forward end slidably related to the rear end of said lower flexible member, and spring means arranged between said rear spar and said tail-portion to supplement the tension of said upper and lower flexible members.

10. A variable camber rib for aeroplane wings having front and rear spars, comprising a flexible body portion consisting of upper and lower flexible longitudinal members having their forward ends fixed to said front spar, a series of compression links intermediate said members and pivotally connected with the latter, means for limiting the flexing movements of said members, a rigid tail-portion having a slidable and oscillatable relation to said rear spar, said rigid tail-portion having the upper portion of its forward end fixed to the rear end of said upper flexible member and the lower portion of its forward end slidably related to the rear end of said lower flexible member, and spring means arranged between said rear spar and said tail-portion to supplement the tension of said upper and lower flexible members.

11. A variable camber rib for aeroplane wings having front and rear spars, comprising a flexible body-portion consisting of upper and lower flexible longitudinal members having their forward ends fixed to said front spar, a series of compression links spaced longitudinally intermediate said members, means for pivoting the ends of said compression links respectively to said upper and lower flexible members, a series of flexible diagonal bracing straps interconnected between said upper and lower flexible members to limit the flexing thereof when desired change of shape from streamline to lifting form is attained, a second series of flexible diagonal straps interconnected between said upper and lower flexible members to limit the flexing thereof

when desired change of shape from lifting to streamline form is attained, and a rigid tail-portion having a slidable and oscillatable relation to said rear spar associated with said upper and lower flexible members and operated by the flexing movements thereof and spring means arranged between said spar and said tail-portion to supplement the tension of said upper and lower flexible members.

12. A variable camber rib for aeroplane wings having front and rear spars, comprising a flexible body-portion having its forward end fixed to said front spar, a rigid tail-portion having a slidable and oscillatable relation to said rear spar, said tail-portion being connected with said flexible body portion whereby upward flexing of the latter produces a limited forward sliding movement upon and a downward swing from said rear spar of said tail-portion, and spring means arranged between said rear spar and said tail-portion to supplement the flexed tension of said flexible body portion.

13. A variable camber rib for aeroplane wings having front and rear spars, comprising a flexible body-portion between said front and rear spars, a rigid tail-portion mounted on and extending rearwardly from said rear spar, the upper portions of said flexible body-portion and said rigid tail-portion being rigidly united while the lower portions of the same are united for limited longitudinal sliding movement of said tail-portion relative to said body-portion, and spring means arranged between said rear spar and said tail-portion to supplement the flexed tension of said flexible body-portion.

14. A variable camber rib for aeroplane wings having front and rear spars, comprising a flexible body-portion consisting of an upper flexible member of shallow channeled steel and a lower flexible member of shallow channeled steel, said members having their forward ends secured to said front spar, an intermediate truss-like structure in articulated inter-connection with said upper and lower flexible members, and a rigid tail-portion having a slidable and oscillatable relation to said rear spar, said tail-portion having the upper portion of its forward end fixed to the rear end of said upper flexible member and the lower portion of its forward end slidably related to the rear end of said lower flexible member.

15. A variable camber rib for aeroplane wings having front and rear spars, comprising a flexible body-portion consisting of an upper flexible member of shallow channeled steel and a lower flexible member of shallow channeled steel, said members having their forward ends secured to said front spar, an intermediate truss-like structure in articulated interconnection with said upper and lower flexible members, a rigid tail-portion

tion having a slidable and oscillatable relation to said rear spar, said tail-portion having the upper portion of its forward end fixed to the rear end of said upper flexible member and the lower portion of its forward end slidably related to the rear end of said lower flexible member and spring means arranged between said rear spar and said tail-portion to supplement the tension 10 of said upper and lower flexible members.

16. A variable camber rib for aeroplane wings having front and rear spars, comprising a flexible body-portion consisting of an upper flexible member of shallow channeled steel and a lower flexible member of shallow channeled steel, said members having their forward ends secured to said front spar, a series of compression links extending between and pivoted by their ends to said upper and lower flexible members, means for limiting the flexing movements of said flexible members, and a rigid tail-portion having the upper portion of its forward end fixed to the rear end of said upper flexible member and the lower portion of its forward end slidably related to the rear end of said lower flexible member.

17. A variable camber rib for aeroplane wings having front and rear spars, comprising a flexible body-portion consisting of an upper flexible member of shallow channeled steel and a lower flexible member of shallow channeled steel, said members having their forward ends secured to said front spar, a series of compression links extending between and pivoted by their ends to said upper and lower flexible members, means for limiting the flexing movements of said flexible members, a rigid tail-portion having the upper portion of its forward end fixed to the rear end of said upper flexible member and the lower portion of its forward end slidably related to the rear end of said lower flexible member and spring means arranged

between said rear spar and said tail-portion to supplement the tension of said upper and lower flexible members.

18. A variable camber rib for aeroplane wings having front and rear spars, comprising a pair of vertically spaced longitudinally extending flexible members having their forward ends fixed to said front spar, and intermediate truss-like structure in articulated interconnection with said flexible members, a rigid tail-portion having a slid- 55 able and oscillatable relation to said rear spar, said tail-portion having the upper portion of its forward end fixed to the rear end of the uppermost flexible member and the lower portion of its forward end slidably 60 related to the rear end of said lowermost flexible member.

19. A variable camber rib for aeroplane wings having front and rear spars, comprising a pair of vertically spaced longitudinally extending flexible members having their forward ends fixed to said front spar, and intermediate truss-like structure in articulated interconnection with said flexible members, a rigid tail-portion having a slid- 65 able and oscillatable relation to said rear spar, said tail-portion having the upper portion of its forward end fixed to the rear end of the uppermost flexible member and the lower portion of its forward end slidably 70 related to the rear end of said lowermost flexible member and spring means arranged between said rear spar and said tail-portion to supplement the tension of said upper and lower flexible members.

In testimony, that I claim the invention set forth above I have hereunto set my hand this second day of July, A. D. 1919.

HUMPHREY FRANCIS PARKER.
